ALBERT J. KOMENAK, OF STAMFORD, CONNECTICUT, ASSIGNOR TO THE EXCELSIOR HARDWARE CO., OF STAMFORD, CONNECTICUT, A CORPORATION OF CONNECTICUT

HASP FOR TRUNK LOCKS

Application filed May 31, 1930. Serial No. 458,548.

This invention relates to hasps for trunk locks, and has for its object to provide a strong and serviceable device of this description, which operates to draw the lid and body of the trunk together into locking relation by a force exerted upwardly against a hook member carried by the trunk body.

This invention has nothing whatever to do with any lock mechanism except that the lower part of the hasp carries lock engaging members, which, when the hasp is forced inwardly, enter suitable openings in the escutcheon plate secured to the trunk body, so that said members may be engaged by the bolt of a suitable lock.

Therefore, no construction of lock will be illustrated or described.

In the accompanying drawings which form a part of this application,

20 Figure 1 is a front elevation showing the position of parts when the hasp is forced downwardly into locking position—

Figure 2 is a section at the line 2—2 of Figure 1 with the parts in locking position and a locking member carried by the hasp engaged with any suitable bolt of a locking mechanism—

Figure 3 is a view similar to Figure 2 but showing the position of the hasp preparatory to forcing the same into locking position—

Figure 4 is a front elevation similar to Figure 1 but showing the hasp member removed, and

Figure 5 is a detail inside view of the hasp member.

Similar numerals of reference denote like parts in the several figures of the drawings.

1 designates the trunk lid, 2 the trunk body, 3 any suitable plate member secured to the lid, and 4 an escutcheon plate secured to the trunk body.

The plate member 3 has secured thereto a block 5 from the bottom of which projects a lug 6, while the plate 4 has secured to its upper end a block 7 which is in alignment with the block 5 and has in its upper face a recess 8 within which the lug 6 enters when the lid is closed, this being an ordinary construction, and while it is not necessary to the

successful operation of the invention, nevertheless its employment is preferred.

The block 7 has its outer face formed into a downwardly extending hook 9 for the purpose presently to be explained.

10 is the hasp which is pivoted at its upper end to the block 3 by means of a pin 11, this hasp being a box-like member having sides 12, and between these sides and near the outer end of the hasp is pivoted a draw bar 13, a pin 14 passing through these sides and the draw bar to effect this pivotal relation.

15 is a spring coiled around the pin 14, one end of the spring bearing against the hasp while the other end bears against the draw bar, the function of this spring being to normally thrust this draw bar outwardly as shown at Figure 3.

Of course, this spring element is very ordinary and any suitable spring performing the same function may be employed.

Extending inwardly from the outer ends of the sides 12 are locking members 16 which have open gates 17, and when the hasp member is forced inwardly these members 16 will enter slots 18 in the plate 4 and be in a position to be engaged by locking bolts in the usual manner.

Presupposing the parts to be in the position shown at Figure 3, the forcing inwardly of the hasp will cause the end of the draw bar 13 to engage the hook 9, and the continued pressure against the hasp will cause this draw bar to be thrust upwardly with considerable force against the hook, and this will draw the lid and trunk body closely together and when the hasp has been forced inwardly so that the locking members 16 have been housed within the slots 18 the pivotal point afforded by the pin 14 will be in a plane inside that of the end of the draw bar, and the final position of the hasp member as the plane of the pin passes inside the plane of the end of the draw bar is accomplished with a spring action

so that it will be clear that when the parts are in the position shown at Figure 2, it will be impossible for the hasp to accidentally become loosened before the lock is operated.

The members 16 have open gates 17 as above described so that when they are in the

position noted at Figure 2 bolts may be operated in a lock construction so that they will enter these gates as shown in the instance of a bolt *a* entering one of the members 16 in Figure 2, and thereby prevent the withdrawal of the hasp.

However, as was stated above, the locking of the hasp has nothing to do with the present invention, and the hasp may be equipped 10 with any suitable appliance that will cooperate with any suitable locking mechanism.

The outer end of the hasp is formed into a finger lift 19 whereby, when the hasp is not 15 locked, force may be exerted to open the hasp.

In the usual form of inventions of this description the hasp member has been carried by the escutcheon plate of the trunk body, 20 and a pivoted draw link has been carried by the hasp, which engages over a hook member carried by the lid of the trunk, so that when the hasp is forced inwardly this hook member will cause a downward pull to be exerted 25 against the hook to thereby draw the lid and the trunk body together, but the present construction is deemed to be a stronger one and to present a much neater appearance.

What is claimed is:—

30 In a trunk lock having a block secured to the trunk body and terminating at its top in a downwardly extending open hook, a plate member secured to the lid of the trunk, a hasp having a base and inwardly extending 35 side portions pivotally swung from said member, a draw bar pivoted at one end between the side portions and extending toward said hook, and spring means carried by said hasp for normally urging said draw bar 40 outwardly, said bar, when the hasp is forced downwardly, being adapted to engage said hook and draw the lid of the trunk tightly against the trunk body.

In testimony whereof I affix my signature 45 hereto.

ALBERT J. KOMENAK.
